UNITED STATES PATENT OFFICE

92,874

DESIGN FOR A GAME DEVICE

Louis E. Baltzley, Glen Ridge, N. J., assignor to Best Manufacturing Co. Inc., Irvington, N. J.

Application December 5, 1933, Serial No. 49,966

Term of patent 14 years

To all whom it may concern:

Be it known that I, LOUIS E. BALTZLEY, a citizen of the United States, residing at Glen Ridge, county of Essex, State of New Jersey, have invented a new, original, and ornamental Design for a Game Device or Similar Article, of which the following is a specification, reference being had to the accompanying drawing, forming part thereof.

The single figure is a perspective view of the game device.

I claim:

The ornamental design for a game device, or similar article, substantially as shown.

LOUIS E. BALTZLEY.
